METHOD OF WEAVING PILE FABRICS

Francis P. Groat, Bloomsburg, Pa., assignor to
The Magee Carpet Company, Bloomsburg, Pa.,
a corporation of Pennsylvania

Original application April 12, 1948, Serial No.
20,547. Divided and this application August
17, 1949, Serial No. 110,787

4 Claims. (Cl. 139—39)

1

This invention relates to a method of weaving pile fabrics and is a division of my prior application, filed April 12, 1948, Serial Number 20,547, now Patent Number 2,546,261, issued March 27, 1951.

In my prior application a pile wire of special shape is disclosed for use in a wire loom to produce weftwise rows of loops of different height. The present invention is directed to the use of this special wire in combination with a cutting wire of conventional type to produce a fabric having rows of loops and rows of tufts, the rows of loops being of different height.

It is an object of the invention to provide a method of weaving a pile fabric with one frame of pile warp to provide a fabric having a background of low loops varying in height in each weftwise row and a raised design of high cut loops or tufts.

Other objects and advantages of the invention will be apparent during the course of the following description.

In the accompanying drawing forming a part of this specification and in which like numerals are employed to designate like parts throughout the same,

Fig. 1 is an exploded side elevational view of a fabric woven in accordance with my invention, and,

Fig. 2 is an exploded perspective view of the fabric in the process of weaving.

Referring to the drawing, the backing of the fabric may be of any suitable construction but in the form illustrated includes the usual stuffer warps 9 and two series of weft threads 10 and 11 lying, respectively, above and below the stuffer warps and bound in place by crossed binding warps 12 and 13. The pile forming warps 14 extend along the fabric in the body thereof between the stuffer warps and the upper series of weft threads 10. When weaving the fabric the pile warps 14 are raised and a loop forming pile wire is inserted in the shed formed by the raised warps. After insertion of the pile wire the warps are lowered forming loops over the wires and pass under the next upper weft thread thus forming a weftwise row of loops 15.

In my improved method a special shaped pile wire 5 is employed in combination with a conventional cutting wire 22. The loop forming edge of the special wire is of undulating shape throughout its length to provide high and low portions 6 and 7 with inclined connecting portions 8 between the high and low portions. The wires 5 are constructed so that when a series are

inserted in the fabric each succeeding wire will have its high and low portions in warpwise alignment with the low and high portions of the preceding wire. The loop forming edge of the cutting wire 22 is straight and is higher than the high portions of the wires 5 with a raised knife edge 21 at its end for severing the loops when the wire 22 is withdrawn.

In wire looms it is customary to insert a series of pile wires in the fabric as it is being woven for a distance of about three inches from the fell or opening of the shed. In carrying out my method the special wires 5 and cutting wires 22 are inserted in the fabric in alternation, with a cutting wire intermediate the special wires and with the high and low portions of each special wire being in warpwise alignment with the low and high portions, respectively, of the preceding special wire. When a special wire 5 is withdrawn the loops formed on the low portions 7 are raised to a height corresponding to that of the loops formed on the high portions 6 so that all the loops 23 in a row are the same height. As the next succeeding special wire is withdrawn the low loops formed thereon will be raised and if formed from the same warps raised in the preceding row, those loops in the preceding row will be lowered, thus forming a weftwise row of high and low loops with the loops in between the low and high loops being of graduated height. When the cutting wires 22 are withdrawn the loops 24 formed thereon will be severed by the knife edge 21 forming weftwise rows of tufts 25. If a warp that has been raised over a special wire 5 is also raised over the next succeeding cutting wire 22, the cutting of the loop by withdrawal of the cutting wire will have no effect on the height of the loop in the preceding row. Also if a warp that has been raised over a cutting wire is raised over a high portion of a special wire the withdrawal of the special wire will have no effect on the tuft formed by withdrawal of the cutting wire, but if the warp is raised over a low portion of the special wire then the withdrawal of the special wire will slightly lower one leg of the tuft.

The pile warps are selectively raised to form the shed for insertion of the pile wires by a Jacquard mechanism operated in accordance with a pattern card of the desired design. By using the special wire in combination with a conventional cutting wire, the ground pile area of the fabric is formed of loops irregular in height and the design area formed of tufts which are higher than any of the loops. With the new method only one frame of pile warps is necessary to pro-

duce a fabric having a pile surface with an embossed or relief effect.

Having thus described my invention, I claim:

1. The method of weaving on a wire loom a pile fabric having a warp pile face including rows of tufts and rows of loops of graduated height which comprises inserting into the shed a non-cutting pile wire having high loop-forming portions and intermediate low loop-forming portions with oppositely inclined loop-forming portions between the high and low portions, weaving pile warps over said high, low and inclined portions to form a weftwise row of high and low pile loops with intervening loops of graduated height between the high and low loops, inserting into a subsequent shed a knife wire having a loop-forming edge of uniform height, selectively weaving the pile warps over said knife wire, inserting into a subsequent shed a second non-cutting wire having high and low loop-forming portions with intervening inclined loop-forming portions, selectively weaving the pile warps over said high, low and inclined portions of said second non-cutting wire to form a succeeding weftwise row of high and low pile loops with intervening loops of graduated height between the high and low loops, withdrawing said first-mentioned non-cutting wire to form a row of high loops, withdrawing said knife wire to form a row of tufts and then withdrawing said second-mentioned non-cutting wire whereby the loops in said first row in pile warps not raised over the intermediate knife wire, but woven over the low and inclined portions of said second non-cutting wire will be reduced in height forming a row of high and low loops with loops of graduated height between each series of high and low loops.

2. A method as described in claim 1 wherein the low portions of one non-cutting wire are in warpwise alignment with the high portions of the other non-cutting wire.

3. A method of weaving a pile fabric having a backing and a plurality of pile warps which comprises forming the backing with the pile warps held therein by elements of the backing, selectively raising the pile warps from the backing to form transverse rows of loops with the loops in alternate rows raised to provide high loops and intermediate low loops with loops of graduated height between the low and high loops, the loops in intermediate rows being raised from those pile warps of the high loops of a subsequent alternate

row to form a row of loops of uniform height cutting the loops in intermediate rows to form rows of tufts, successively raising the low loops and loops of graduated height in alternate rows to the height of the high loops whereby the height of the loops in each preceding alternate row of loops of those pile warps not raised in intermediate rows are reduced in height.

4. The method of weaving on a wire loom a pile fabric having a warp pile face including rows of tufts and rows of loops of graduated height which comprises inserting into the shed a non-cutting pile wire having high loop-forming portions and intermediate low loop-forming portions with oppositely inclined loop-forming portions between the high and low portions, weaving pile warps over said high, low and inclined portions to form a weftwise row of high and low pile loops with intervening loops of graduated height between the high and low loops, inserting into a subsequent shed a knife wire having a loop-forming edge of uniform height, selectively weaving the pile warps over said knife wire, inserting into a subsequent shed a second non-cutting wire having high and low loop-forming portions with intervening inclined loop forming portions, selectively weaving the pile warps over said second non-cutting wire with the pile warps that are woven over said knife wire being woven over the high portions and the pile warps that are not woven over said knife wire being woven over the low and inclined portions, withdrawing said first-mentioned non-cutting wire to form a row of high loops, withdrawing said knife wire to form a row of tufts and then withdrawing said second non-cutting wire whereby the loops in said first row in pile warps woven over the low and inclined portions of said second non-cutting wire will be reduced in height forming a row of high and low loops with loops of graduated height between each series of high and low loops.
